TWISTING TOOL

Filed March 22, 1929

INVENTOR.

Charles F. Bailey

Charles LaPorte

A. T. Y.

UNITED STATES PATENT OFFICE

CHARLES F. BAILEY, OF PEORIA, ILLINOIS, ASSIGNOR TO WILLIAM H. SOMMER, OF PEORIA, ILLINOIS

TWISTING TOOL

Application filed March 22, 1929. Serial No. 349,190.

This invention has reference to twisting tools, and it has for its principal object to provide a tool for manual operation which may be quickly and efficiently applied to a 5 wire fastener for securing the stringer elements of a revetment, such for instance as the stringer elements employed in connection with an articulated concrete mattress used to prevent scouring or erosions of river banks.

10 Reference is had to companion applications, filed of even date herewith, bearing Serial Nos. 349,191, 349,189, respectively, which show a fastener such as operated on by my tool and also the use of the fastener in re- 15 vement work.

That the invention may be more fully understood, reference is had to the accompanying drawings forming part of this description, illustrating a preferred embodiment of 20 the invention, in which:—

Fig. 1 is a view in elevation, on a reduced scale, showing a twisting tool embodying my invention;

25 Fig. 2 is a detail in elevation, partly in section, showing the manner of applying the twisting portion of the tool to a wire fastener which is shown in dotted lines;

Fig. 3 is a view similar to Fig. 2 and of the same parts, except that the fastener, shown 30 in dotted lines, is secured in twisting position in the tool;

Fig. 4 is a view somewhat similar to Fig. 3, except that the fastener, shown in dotted lines, is here shown twisted about the stringer 35 elements of a revetment;

Fig. 5 is a cross-section as the same would appear if taken on the line 5—5, Fig. 2;

Fig. 6 is a cross-section as the same would appear if taken on the line 6—6, Fig. 2, and 40

Fig. 7 is a view in elevation showing a modified means for turning the tool when twisting.

Like characters of reference denote corresponding parts thruout the figures.

45 The fastener A shown in dotted lines in Figs. 2, 3 and 4, is the fastener forming the subject matter of my companion application bearing Serial No. 349,191, and is formed from a single length of wire bent on itself 50 to provide the arcuate bend *a* from which ex-

tend the legs *b* and *c*, the former shorter than the latter and the ends of each leg formed with the right angle bends *d* and *e*, respectively. The bend *d* on the leg *b* turned away from the leg *c* and the bend *e* on the leg *c* turned toward the leg *b* and having a relation so as to provide the throat *f* therebetween.

The tool adapted for twisting the legs *b* and *c* with each other, as at *g* in Fig. 4, to secure the stringer elements *h* of a revetment comprises a stem 1, of suitable length to which is connected and extends therefrom a holder 2. In one form the stem 1 has a hand-hold 3 for manual gripping whereby to turn the tool for twisting the legs *b* and *c* of the fastener A. In another form, see Fig. 7, the stem 1 is provided thruout with a double thread 4 cut therein and slideable on the stem is a sleeve 5 having a hand-hold 6 and 60 inferiorly disposed nuts or members 7 operative in the threads 4, so that as the sleeve 5 is moved along the stem and the nuts or members 7 caused to traverse the threads 4, the tool is turned, as will be understood.

The holder 2 is preferably an elongated substantially flat channel-like member having two side walls 8, with one side open, as at 9, and with a rear wall 10 extending down from the stem to a point removed from the lower end of the holder, as at 11, leaving the lower end of the holder open between the side walls 8, 8, see Fig. 2. A bridge member 12, which is preferably inclined to the axis of the holder and of an upwardly tapered form connects the lower ends of the side walls 8 and beyond and outside said side walls the ends of the bridge project to provide protruding stops 13, to limit the downward movement of a sleeve 14 embracing and slideable on the holder 2. That wall of the sleeve 14 coincident with the open side 9 of the holder has the rounded or beveled lower inner portion 15.

Provision is made to hold the sleeve 14 in twisting and non-twisting positions on the holder 2, which consists in providing the outer face of one of the side walls 8 of the holder 2, near the upper and lower ends thereof with ball-seats 16, see Figs. 1, 3, 5 and 7, and

adapted to coact with and become seated in said seats, is a ball-lock 17 yieldingly held by a spring 18 disposed in a base 19 projecting laterally from the face of the holder, see Fig. 5. It is obvious, therefore, that the sleeve 14 may be caused to have a slidable movement on the holder toward and from the stem 1 and be held in these different positions by the ball-lock 17, becoming seated in a ball-seat 16. The spring 18 applies the necessary force to hold the ball in a seat to lock the sleeve but will yield readily to pressure applied to the sleeve to move it to its different positions, as shown in the several figures. A stiffening member 20 is disposed transversely within the holder 2 connecting the side walls 8, midway the length of the holder and yet out of way to avoid interference with the application of the tool to a fastener A.

20 To use the tool to apply a fastener A for securing the stringer elements h of a revetment, such as is illustrated in my companion application bearing Serial No. 349,189, the fastener is first applied to the stringer h, by 25 passing the long leg b under the stringer, which latter enters the throat f of the fastener and is seated in the arcuate end of the fastener between the legs b and c thereof. A person handling the tool will first see that the sleeve 14 is in non-twisting position shown in Fig. 2 and on applying the twisting head 2 to the fastener, the legs of the fastener are caused to enter the open side 9 of the head with the angular end d overlying the bridge 12 and the angular end e resting against the wall 10, see Fig. 2. With the fastener in this position in the head 2 of the tool, the sleeve 14 is moved downwardly into twisting position until brought to rest on the stops 13 and during such downward movement of the sleeve the rounded or beveled portion 15 of the sleeve will ride against the leg c of the fastener and cause the fastener to assume the position shown in Fig. 3, with the throat 45 f, partially formed by the angular end d and the straight body portion of the leg c, practically closed. In this position the angular ends d and e lie in the sleeve 14 between the side walls 8, and this space being a shallow 50 space, the ends of the fastener cannot slip or turn and when the tool is turned, the arcuate end of the fastener being anchored against the stringer elements h, the turning of the head and sleeve will apply force against the 55 angular ends of the fastener and cause a twisting of the legs b and c together, as at g, see Fig. 4. When the twisting action is completed, the sleeve 14 is moved to non-twisting position permitting the head 60 2 to be easily and conveniently removed from the secured fastener. The wall 10 is cut-off short of the lower end of the tool so that there is nothing to interfere with or retard the placing of the angular end d of the 65 fastener over the bridge 12 and the wall 10

higher up provides a stop for the angular end e of the fastener, so that the fastener will assume its proper position within the tool.

What I claim is:—

1. A twisting tool for securing wire fasteners to revetment work, comprising a head arranged for the reception of the twisting ends of a fastener therewithin, and a member having movable relation with respect to the head and adapted to engage and secure a fastener in a twisting position on the head. 70

2. A twisting tool for securing wire fasteners to revetment work, comprising a slotted head adapted to receive twisting ends of a fastener therewithin, and a member 80 slidable on the head adapted to engage and secure a fastener in twisting position.

3. A twisting tool for securing wire fasteners to revetment work, comprising a head slotted along one edge and at its end to receive a fastener therewithin, a wire engaging bridge crossing said slotted end, and a member 85 slidable on the head and having a wall adapted to be moved across the slotted edge of said head and to bear against the fastener to secure the same in twisting position in the head. 90

4. A twisting tool for securing wire fasteners to revetment work, comprising a shallow elongated head having two side walls 95 and a rear wall terminating short of the end of the head, whereby to provide an open slotted edge and open end to receive the ends of a wire fastener therebetween, and a member 100 slidable on the head adapted to engage and secure a fastener in twisting position.

5. A twisting tool for securing wire fasteners to revetment work, comprising a shallow elongated head having two side walls and a rear wall terminating short of the end of the head, whereby to provide an open slotted edge and open end to receive the ends of a wire fastener therebetween, a member 105 slidable on the head adapted to engage and secure a fastener in twisting position, and means complementary to the head and member, whereby the member and head may have a locking relation in different positions of the member. 110

6. A twisting tool for securing fasteners to revetment work, comprising a slotted head adapted to receive twisting ends of a fastener therewithin, a handle for turning said head, and a member having a slidable and telescopic movement on said head adapted to engage and secure a fastener in twisting position in said head. 115

7. A tool for securing wire fasteners to revetment work, comprising a shallow elongated head slotted along one edge and at its end to receive the spaced ends of a pre-formed wire fastener therewithin, a bridge across the slotted end of the head to receive one end of the fastener, and a member 125 telescopically slidable on said head and having 130

a wall adapted to overlie the slotted edge of the head and engage another end of the fastener, whereby to secure said fastener within the head in twisting position.

- 5 8. A tool for securing wire fasteners to revetment work, comprising a shallow elongated head slotted along one edge and at its end to receive the spaced ends of a pre-formed wire fastener therewithin, a bridge across the slotted end of the head to receive one end of the fastener, a member telescopically slid able on said head and having a wall adapted to overlie the slotted edge of the head and engage another end of the fastener, whereby to secure said fastener within the head in twisting position, and means complementary to the head and member, whereby the member and head may have a locking relation in different positions of the member.
